CLIP FOR SECURING TOGETHER THE COVERS AND RIBS OF UMBRELLAS

John A. Maxwell, Jr., Lancaster, Pa.

Application March 8, 1937, Serial No. 129,747

2 Claims. (Cl. 135—36)

Where fastening of umbrella covers to the rib between the top notch and the tip of the rib is desired, these fastenings should be inconspicuous, readily and quickly applied and should be permanent, and unlikely to be disrupted by the opening and closing of the umbrella or by wind.

I have devised a clip that fulfills these conditions, and requires for setting into place only a slightly modified standard staple setter and pliers. The standard umbrella is composed of gores that are substantially triangular. The most acute angle of the gores lies at the top notch. The gores are sewed to each other at their sides forming, beyond the line of the stitches, a fell, or allowing the two strips of material beyond the line of stitches to project unfelled downward from the lower side of the cover. The third side of these triangular gores forms the periphery of the umbrella, and is finished by a selvage or hem, or other finish that will prevent fraying.

My device is intended to hold the cover to the rib, part way between the top notch and the end of the rib, in such a way that the connection between these two parts is very permanent, secure, and not disruptable by any reasonable use. My device is much more readily and quickly applied to fastening together the rib and cover than any previous connection heretofore made between them. The device also does not have an offensive appearance but is inconspicuous, as it fits closely and smoothly around the rib, and the means by which it is attached to the cover are completely or almost hidden. The part enclosing the ribs may be polished or have the same color and texture as the rib, and, by its use, the appearance of the lower side of the cover is improved over what it would have been if the previously used means were employed for securing together the rib and the cover partway between the top notch and rib tip. The instrument for setting the device may be the ordinary stapling plier with the addition of a small swaging anvil. My device may be placed by hand at the point of its attachment to the cover, and the fastening of it to the cover completed by a single squeezing of the handle of the pliers. Without undue haste a worker can finish setting my devices in two umbrellas in a minute, in continuous work. While I do not claim the stapling device in this application, I have illustrated its operation in showing the advantages of my device. The drawing and the detailed description below are also illustrative. Details therein, not re-

ferred to in a claim, must not be taken as limiting my invention as defined in such claims.

Fig. 1 is a view of the lower side of the cover of an umbrella illustrating the general positioning of my device on the ribs and cover. Fig. 2 is a perspective of my device open before it is applied to the umbrella cover. Fig. 3 is a detail showing the side of my device that lies in position toward the cover with the staple ready to be set to fasten the clip to the fabric. Fig. 4 is a like view of the clip with the staple driven into its fastening position holding the clip to the fabric of the umbrella. Fig. 5 shows the clip in engagement with the stapling pliers. Fig. 6 is a cross section through the rib, cover and clip, with staple in fastening position holding clip to fabric and the clip closed on rib. Fig. 7 is a view of clamping pliers for closing clip around frame rib.

The clip has a pair of clamping leaves 3, 3, that embrace the rod 2, when the clip is secured permanently to the rib. Before the clip is applied to the umbrella these arms are spaced from each other, leaving a space between the edges a, a, of these leaves 3, 3, wide enough to allow the rib to be passed between them. The clip has at its side away from the opening between the edges a, a, the openings 5, 5. These openings are each large enough in diameter to receive the side arms 6, 6, of the staple 4, that, before passing through the holes 5, 5, pass through the portions 7, 7, of the cover 1, that lie beyond the seam 9 by which the gores of the cover are united to form the complete cover. The back 19 of the staple lies against the fabric. In most umbrellas the portions 7, 7, of the cover fabric are folded over on each other to form a fell, such as is shown and is marked as a whole 22, and so afford a particularly firm anchor for the back 19 of the staple, because the arms 6, 6, pass twice through at least one gore. The arms 6, 6, pass through the holes 5, 5, and are bent, then by engaging the rod against the inside of the clip when the clip is set the arms are retained on the rigid material of the clip and fasten the fell 22 and clip very tightly together. When the leaves 3, 3, are pressed down on the rod 2, the staple may be placed so that it is not seen, because its back may lie entirely beneath the rod 2, and the fell 22. I arrange it to be so placed when I use my clip in practice.

The clip is usually of malleable sheet metal, may be chromium or otherwise plated, and may be polished and is scarcely noticeable in the open, complete umbrella. If properly made and

set it lies smoothly and closely upon the rib, has no discernible fastening to the cover although it is tightly indeed immovably secured to it, and the attachment between it and the cover is practically unobservable, especially when the staple passes through a fell.

Some changes may be made in the device as shown and described above without departing from my invention and, accordingly, I do not limit my invention to less than is claimed.

I claim:—

1. A fastening for securing the fabric of the cover and ribs of an umbrella together at a point part way between the top notch and the rib tip, comprising a clip having a pair of leaves with

free edges and malleable enough to be bent around a rib of the umbrella but sufficiently rigid to retain their shape when so bent, and having a back portion connecting and integral with the leaves, and having holes therein, in combination with a staple passing through the fabric of the cover and through the holes in the back of the clip, and having arms bent over on the inside of the clip, and a back lying against the fabric of the cover.

2. The device defined in claim 1, having the leaves extending sufficiently along the rib to immovably clasp the clip to the rib.
